(57) **CLAIM**

The ornamental design for a hairpin, as shown and described.

DESCRIPTION

FIG. 1 is a front, right and top perspective view of a hairpin, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of the hairpin shown in an alternate open configuration; and,

FIG. 10 is an enlarged view of a portion of the hairpin shown within the area designated as 10 in FIG. 1.

The broken lines shown in the drawings illustrate portions of the hairpin that form no part of the claimed design.

The dot-dash broken lines depict the boundaries of the enlargements that form no part of the claimed design.

1 Claim, 10 Drawing Sheets
